CLAIM

The ornamental design for a microderm abrasion machine, as shown and described herein.

DESCRIPTION

FIG. 1 is a top perspective view of a microderm abrasion machine incorporating the claimed design;

FIG. 2 is a front plan view thereof;

FIG. 3 is a top elevational view thereof;

FIG. 4 is a right side plan view thereof, the left side being a mirror image thereof;

FIG. 5 is a back elevational view thereof; and,

FIG. 6 is a bottom elevational view thereof.

The broken lines in the drawings depict unclaimed environmental subject matter.
